UNITED STATES PATENT OFFICE

BENJAMIN F. CONNER, OF WETHERSFIELD, CONNECTICUT, ASSIGNOR TO COLT'S PATENT FIRE ARMS MANUFACTURING CO., OF HARTFORD, CONNECTICUT, A CORPORATION OF CONNECTICUT

DESIGN FOR A BOTTLE CAP

Application filed September 17, 1932. Serial No. 44,961. Term of patent 7 years.

To all whom it may concern:

Be it known that I, BENJAMIN F. CONNER, a citizen of the United States, residing at Wethersfield, in the county of Hartford and State of Connecticut, have invented a new, original, and ornamental Design for a Bottle Cap, of which the following is a specification, reference being had to the accompanying drawing.

Of the drawing:

Fig. 1 is a plan view of a bottle cap embodying my new design.

Fig. 2 is a side view.

Fig. 3 is a fragmentary sectional view taken on line 3—3 of Figure 1.

I claim:

The ornamental design for a bottle cap as shown.

BENJAMIN F. CONNER.
